UNITED STATES PATENT OFFICE.

WALTER E. MILESTONE, OF LAKEWOOD, OHIO.

DESIGN FOR A CABINET FOR FLUID-DISPENSING OUTFIT.

Application filed December 23, 1927. Serial No. 24,609. Term of patent 3½ years.

To all whom it may concern:

Be it known that I, WALTER E. MILESTONE, a citizen of the United States, residing at Lakewood, in the county of Cuyahoga and State of Ohio, have invented a new, original, and ornamental Design for Cabinet for Fluid-Dispensing Outfit, of which the following is a specification, reference being had to the accompanying drawing, forming part hereof, wherein the figure is a perspective view of a cabinet for fluid dispensing outfit showing my new design.

I claim:

The ornamental design for a cabinet for fluid dispensing outfit as shown.

WALTER E. MILESTONE.
